[57] CLAIM

The ornamental design for a closure cap for a bottle or the like, as shown.

DESCRIPTION

FIG. 1 is a top perspective view of a closure cap for a bottle or the like showing my new design;

FIG. 2 is a top plan view;

FIG. 3 is a side elevational view;

FIG. 4 is a side elevational view showing the side opposite that seen in FIG. 3; and

FIG. 5 is a bottom plan view.
